ANTHONY UTZ, OF HARTFORD, CONNECTICUT, ASSIGNOR TO ROYAL TYPEWRITER COMPANY, OF NEW YORK, N. Y., A CORPORATION OF NEW JERSEY.

TYPE-WRITING MACHINE.

1,028,159.

Specification of Letters Patent.

Patented June 4, 1912.

Application filed March 24, 1911. Serial No. 616,650.

To all whom it may concern:

Be it known that I, ANTHONY UTZ, a citizen of the United States of America, residing in Hartford, county of Hartford, 5 State of Connecticut, have invented a certain new and useful Improvement in Type-Writing Machines, of which the following is a specification.

This invention relates to line space devices of a rotatable cylinder typewriting machine. Its purpose is to simplify and cheapen such devices and at the same time to afford a clearly observable definite indicator of the line space adjustment.

15 The invention is shown applied to line space devices of the general construction disclosed in the patent of Edward B. Hess, No. 856,869, granted June 11, 1907.

In the accompanying drawing: Figure 1 20 is a detail section taken transversely to the platen axis adjacent the left hand end plate of the carriage: Fig. 2, a front elevation of what is shown in Fig. 1: Fig. 3, a sectional view, similar to Fig. 1, with the parts in 25 a different position: and Fig. 4, a front elevation of the devices shown in Fig. 3.

a indicates the left hand side plate of the carriage.

c is one member of a clutch joint formed 30 on the hub of the line space ratchet wheel *d*, the other member of which clutch is carried at the end of the platen (not shown) and of which *e* is the shaft having applied to it the usual turning knob. The ratchet wheel 35 and its hub are appropriately connected with the platen shaft by set screws or otherwise. On the outer side of the ratchet wheel and rocking loosely upon the hub thereof is a radial arm *f* in the end of which 40 is pivoted a ratchet wheel push pawl *g*, a spring *h* being applied around the pivot bolt of the pawl and tending constantly, by its reaction, to draw the end *g'* of the pawl into engagement with the teeth of the 45 ratchet wheel.

k indicates a link pinned to the radial arm *f* and operated in the manner disclosed in the aforesaid patent of Edward B. Hess, or otherwise, to swing the radial arm rearwardly and carry the pawl *g* in engagement 50 with the ratchet wheel to turn the platen for line space purposes.

o is the flanged guard or shield rocking 55 on the hub of the ratchet wheel and the flange *o'* of which overlies the periphery of

the ratchet wheel. This shield is adjustable, as is well understood, so that the rear edge of the upper part of the flange will control engagement of the end *g'* of the actuating pawl with the teeth of the ratchet 60 wheel.

The construction comprising the rocking arm *f*, link *k*, ratchet wheel shield or guard *o* and the detent pawls for the ratchet wheel and its shield are all as disclosed in the 65 aforesaid Letters Patent and behave in the same way and therefore more detailed description of them seems unnecessary. As in the Hess patent, the front face of the flange overlying or embracing the periphery of the 70 ratchet wheel is marked with numbers to indicate the adjustment of the line space, these markings being 0, 1, 2, 3 as seen in Fig. 2.

The present invention resides in the peculiar construction and behavior of the pawl *g*. Its rear or ratchet wheel actuating end *g'* engages the teeth of the ratchet wheel and the position of the shield determines at what point in its movement it may engage 80 the wheel. The other end *g''* of the pawl, which is extended in front of its axis, serves as a marker or pointer that overlies the flange of the guard and is so proportioned, arranged and adapted as to act as an indicator or pointer in connection with the numerals or other markings that may be placed 85 on the guard to indicate to the operator what is the line space adjustment. Thus, in Fig. 2, it will be seen that the pointer which 90 is the end *g''* of the ratchet wheel pawl lies immediately below or beyond the numeral 3, thus indicating that the adjustment of the shield is such that the engagement of the pawl with the ratchet wheel will result in a 95 movement of the platen 3 through the arc of three ratchet wheel teeth.

In Fig. 4, the adjustment is such that there will be a movement of the platen through the arc of but one ratchet wheel tooth, the pointer *g''* being immediately above the numeral 1. This front end of the pawl is not shown as of the same width, or substantially the width, of the guard *o* but it obviously might be so. In the form in 100 which it is illustrated, it substantially covers such numerals or markings on the guard *o* as lie above its lower edge. The indication of the adjustment is therefore very characteristic and readily observable without any 105 110

possibility of confusion and this result is obtained without the addition of a special pointer. Such special pointers have heretofore been provided and they have usually 5 consisted of a separate piece attached to a proper part of the machine and arranged to extend toward or over the flange of the guard from the side thereof. The indication that they give is not therefore so definite and so readily read as that obtained by 10 the present construction.

I claim:

- 15 1. A line space mechanism comprising the combination of the platen ratchet wheel, its adjustable flanged guard having upon the flange thereof characters indicating different line space adjustments, a swinging arm to be actuated by the operator, a pawl pivoted in said arm and one end of which is 20 adapted to engage and drive the ratchet and the other end of which co-operates with the line space indications on the flange of the guard to indicate to the operator the adjustment of the devices.
- 25 2. Line spacing mechanism comprising

the combination of the platen ratchet wheel, its adjustable flanged guard having line space indicators, a movable pawl support, a pawl pivoted therein and adapted to actuate the ratchet wheel and a line space indicator moving with said support and co-operating with the indications on the guard. 30

3. Line spacing mechanism comprising the combination of the platen ratchet wheel, an adjustable guard having characters indicating the line spacing, a swinging pawl support, a pawl pivoted therein and adapted to actuate the ratchet wheel and a line space indicator moving back and forth with the pawl and arranged to overlie those line 40 space indications on the guard that are, in any of the positions of adjustment, above and beyond its end.

In testimony whereof, I have hereunto subscribed my name.

ANTHONY UTZ.
